UNITED STATES PATENT OFFICE.

JAMES H. LIPSCOMB, OF BOKCHITO, OKLAHOMA.

KNOCK-DOWN COOP.

Application filed September 23, 1927. Serial No. 221,527.

This invention has reference to shipping crates especially designed for use in shipping poultry or other live stock, the primary object of the invention being to provide a 5 shipping crate of the knock-down type so that the sides and ends of the crate may be readily and easily disconnected and secured together for return shipment.

An important object of the invention is 10 to provide a shipping crate of this character which will be exceptionally strong and durable when in its extended position, to the end that shipping crates when filled with live stock may be piled one upon another to 15 facilitate the shipment thereof.

A still further object of the invention is to so construct the sides and ends of the crate that the securing bolts will be guarded eliminating any possibility of live stock 20 shipped in the crate being injured by contact with the securing bolts.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 25 30 within the scope of what is claimed, without departing from the spirit of the invention.

Referring to the drawings:

Figure 1 is a vertical sectional view through a shipping crate constructed in accordance with the invention.

Figure 2 is a sectional view taken on line 2-2 of Figure 1.

Figure 3 is a vertical sectional view taken on line 3-3 of Figure 1.

Figure 4 is a fragmental perspective view showing the manner of securing the corners of the sections of the crate.

Referring to the drawings in detail, the crate includes a bottom 5 which is constructed preferably of wood, however it is to be understood that any desirable material may be employed in the construction of the bottom.

The bottom is braced against bulging under 50 the weight of the contents of the crate by means of the bracing bands 6 that extend between opposite corners, crossing each other at the center of the bottom, where they are secured to the bottom by means of the bolt 55 7. Each of the side sections of the crate includes upper and lower angle bars 8

formed preferably of sheet metal, while the vertical end bars of each side section also embody angle bars arranged so that the open sides thereof extend outwardly as shown 60 by the drawings, the end bars being indicated by the numeral 9.

Each of the end sections of the crate includes upper and lower angle bars 10 and side angle bars 11, the latter angle bars 65 also having their open sides disposed outwardly, to the end that when the end bars of the side and end sections of the crate are brought together, they define housings for the bolts, to be hereinafter more fully described.

It will also be seen that due to this construction, the upper and lower bars of the side and end sections overlap each other, where they are provided with openings to 75 receive the elongated securing bolts 12 that are supplied with nuts so that the sections of the crate will be drawn into close engagement with each other when the nuts are tightened on the threaded ends of the bolts. 80

These nuts are indicated by the reference character 13 and while they act to hold the sections of the crate together, they also hold the cover which is indicated at 14, to the 85 crate.

This cover is formed preferably of wire mesh material and as shown, the bolts pass through the mesh, washers being provided for insuring a close fit.

The frames of the side and end sections 90 are covered with suitable wire mesh material as clearly shown by the drawings.

From the foregoing it will be seen that by removing the nuts 13, the bolts may be readily removed, to the end that the side and end sections may be laid one upon the other and secured in any suitable manner, to the end that it will require but little space for the return shipment of the crate.

I claim:

1. A shipping crate for shipping live stock including a bottom section, side and end sections, the side and end sections being formed of wire mesh material, said side and end sections including vertical end angle bars arranged with their open sides disposed outwardly, bolts extending through the sections for holding the sections together, the angle bars at the ends of the sections defining housings, and a cover constructed of wire mesh material for closing the upper portion of the crate.

2. A shipping crate for shipping live stock including a bottom section, side and end sections, said side and end sections including upper and lower angle bars, end angle bars connecting the upper and lower angle bars and having their open sides disposed outwardly, the end angle bars of the sections overlapping each other to define housings, bolts extending through the housings
- 5

for connecting the sections, wire mesh material secured to the angle bars of the sections, and a cover of wire mesh material for closing the upper portion of the crate. 10

In testimony that I claim the foregoing as my own, I have hereto affixed my signature. 15

JAMES H. LIPSCOMB.
